GRINDING DEVICE FOR REVOLVING CUTTERS

Raymore D. MacDonald, Western Springs, Ill.,
assignor to International Harvester Company,
a corporation of New Jersey

Application July 7, 1934, Serial No. 734,122

4 Claims. (Cl. 51—246)

This invention relates to a knife grinding device. More specifically it relates to a knife grinding attachment for machines having a rotor which carries cutting blades.

5 The principal object of the present invention is to devise and construct a knife grinding attachment particularly adapted for sharpening the blades of a rotary cutter without removing the rotor or the blades from the machine of
10 which it is a part.

Another object is to provide a knife grinding attachment as above set forth which may be resiliently mounted to apply proper pressure to a grinding means without subjecting the grinding
15 element to destructive impacts and pressures.

Another object is to provide a means which can be reciprocated in a grinding device to traverse a long blade without utilizing a large and expensive grinding element.

20 Another object is to provide a grinding device which is particularly adapted for grinding blades of rotors of spiral or other shape which describe in their rotation a surface of revolution, whereby the stone may be reciprocated to cover the entire
25 edges of the blades which lie in the surface of revolution.

These objects and others which will be apparent from the detailed description to follow are accomplished by a device as illustrated in the
30 drawing when utilized as set forth in the description of the operation which follows.

In the drawing:

Figure 1 is a cross section through a casing in which a rotor is mounted for operation and on
35 which a grinding device embodying the invention has been mounted;

Figure 2 is a side elevation of the construction shown in Figure 1, illustrating particularly the grinding device; and,

40 Figure 3 is a detail view of the supporting means for the grinding device on the rotor supporting casing.

As this invention relates only to the knife or blade sharpening device, only a portion of a casing 10 has been shown. This casing may be a part of any material reducing means, such as an ensilage harvester or cutter, or other feed reducing means. A rotor 11 is mounted in the casing 10 on a transverse shaft 12, means not shown being provided for rotating the shaft 11. The rotor 10 carries at its periphery spiral blades 13 which are rigidly secured in position by bolts 14. These spiral blades are so shaped that during rotation their cutting edges 15 generate in a
55 geometric sense a cylinder of revolution. For

certain particular purposes it might be found advisable in machines of this nature to arrange straight or spiral blades, the cutting edges of which would generate conical surfaces of revolution during operation. This point is mentioned, as the grinding attachment may be utilized equally well on rotors, the blades of which follow either conical or cylindrical surfaces.

On the parallel side walls 16 of the casing 10 brackets 17 are pivoted on a transverse axis 10 parallel to a line lying in the surface of revolution defined by the knife edges 15. In the embodiment illustrated the brackets are pivoted on an axis parallel to the axis of the shaft 12, and likewise the other parts to be hereinafter described will be parallel to this axis.

Two slide bars 18 are secured in spaced relation to the brackets 17, said bars being parallel to each other and parallel to the axis of the shaft 12. The bars 18 and the brackets 17 provide a pivotally mounted supporting frame on which a supporting structure 19 for the grinding element is slidably mounted. As shown in Figure 3, alternate ends of the bars 18 are secured to the respective bracket 17, the other ends being slidably mounted in the bracket. This construction provides for easy removal of the supporting frame and of the grinding stone support therefrom.

30 The structure 19 consists of a center member 20 provided with bearing portions 21, which slidably engage the bars 18 and a pair of bearing caps 22, which, with the bearing portions 21, form a slidable mounting for the supporting structure on the cross bars 18. The caps 22 are secured by cap screws to the member 20.

35 A cup-like portion 23 of the center member 20 is formed to receive a suitable grinding stone 24, which is rigidly secured in the pocket. Said stone is provided with a flattened face to engage the edges 15 of the blades 13 as they are rotated about their supporting axes. As the supporting structure 19 is reciprocated transversely of the bars 18 the grinding stone 24 traverses the entire edges of the blades 13, it being understood that the rotor is in motion during reciprocation of the grinding stone.

40 To provide means for holding the supporting frame resiliently in position, two threaded members 25, pivoted on the side walls 16 of the casing, extend through openings 26 formed in right angled extensions of the brackets 17. Springs 27 abut the members 25 adjacent their pivotal connections at one end and abut the inside portion of the brackets 17 at their other end.

55

Springs 28, which are relatively stronger than the springs 27, abut the outer sides of the brackets 17 at one end and abut a threaded hand nut 29 at their other end. Spring held latches

5 30 mounted on the brackets 17 engage suitable notches 31 in the hand nuts 29 for holding said nuts against turning during vibration incident to operation of the grinding device.

The supporting brackets 17 are mounted, as 10 previously described, to provide with the bars 18 a slidable support for the grinding element supporting structure 19. The upper end of the pivoted brackets 17 are resiliently held in position by the springs 27 and 28. By providing the 15 springs 28 stronger than the springs 27, the grinding stone may be tilted toward the rotor by tightening the hand nuts 29. There is sufficient flexibility in the connections of the bars 18 with the brackets 17 to permit slight relative angular 20 movement of the brackets 17 by adjusting only one of the hand nuts 29. By this means the guide bars 18 may be adjusted to bring movement of the stone 24 into a parallel line with the contact line in the surface of revolution 25 generated by the knife edges 15.

To provide means for readily reciprocating the grinding stone supporting structure 19, a rod 32 secured to the structure extends laterally through an opening in the side wall 16 and is 30 provided at its outer end with a bent down portion which may be grasped by the operator. By the provision of this means the grinding stone support may be readily reciprocated over the surface of the rotor during rotation thereof, 35 whereby the edges of all of the blades may be engaged and sharpened.

It is to be understood that applicant has shown and described only a preferred embodiment of his knife grinding attachment for the 40 blades of rotors, and that he claims as his invention all modifications falling within the scope of the appended claims.

What is claimed is:

1. A sharpening device for a material reducing 45 machine having a supporting structure, a rotor mounted for rotation thereon, and blades mounted on the rotor positioned with their cutting edges following a cylindrical path, and in combination therewith; a supporting frame pivotally mounted on the supporting structure on an axis parallel to the axis of the rotor, a support 50 mounted for reciprocation on said frame, a grinding stone carried by said support, means for reciprocating the support whereby the stone is moved along the cylinder of revolution defined by the edges of the blades, and manually 55 adjustable resilient means for holding the sup-

porting frame in position and for urging the frame toward the cutting blades.

2. A sharpening device for a material reducing machine having a casing, a rotor mounted for rotation in the casing, and blades mounted on 5 the rotor positioned with their cutting edges following a cylindrical path, and in combination therewith; two spaced brackets pivotally mounted on an axis parallel to the axis of the rotor, supporting bars secured to the respective brackets 10 at one of their ends and slidably carried at their other ends by the other brackets, said bars being parallel to the axis of the rotor, a support mounted for reciprocation on said bars, a grinding stone carried by said support, and 15 means for reciprocating the support whereby the stone is moved along the cylinder of revolution defined by the edges of the blades.

3. A sharpening device for a material reducing machine having a casing, a rotor mounted 20 for rotation in the casing, and blades mounted on the rotor positioned with their cutting edges following a cylindrical path, and in combination therewith; two spaced brackets pivotally mounted on an axis parallel to the axis of the rotor, 25 two spaced supporting bars mounted on said brackets parallel to the axis of the rotor, a support mounted for reciprocation on said bars, a grinding stone carried by said support, means for reciprocating the support whereby the stone 30 is moved along the cylinder of revolution defined by the edges of the blades, and resilient, manually adjustable means for holding the brackets in position and for urging the brackets 35 toward the rotor and the grinding stone carried thereby against the cutting edges of the blades.

4. A sharpening device for a material reducing machine having a casing, a rotor mounted for rotation in the casing, and blades mounted on the rotor positioned with their cutting edges 40 following a cylindrical path, and in combination therewith; two spaced brackets pivotally mounted on an axis parallel to the axis of the rotor, two spaced supporting bars mounted on said 45 brackets parallel to the axis of the rotor, each of said bars being slidable with respect to one bracket to facilitate removal, a support mounted for reciprocation on said bars, a grinding stone carried by said support, means for reciprocating the support whereby the stone is moved along 50 the cylinder of revolution defined by the edges of the blades, and resilient, manually adjustable means for holding the brackets in position and for urging the brackets toward the rotor and the grinding stone carried thereby against the 55 cutting edges of the blades.

RAYMORE D. MacDONALD.
